UNITED STATES PATENT OFFICE.

KARL P. McELROY, OF WASHINGTON, DISTRICT OF COLUMBIA, ASSIGNOR TO CHEMICAL DEVELOPMENT COMPANY, OF WASHINGTON, DISTRICT OF COLUMBIA, A CORPORATION OF MAINE.

MANUFACTURE OF ALKALIS.

1,264,536.

Specification of Letters Patent. Patented Apr. 30, 1918.

Application filed June 22, 1915. Serial No. 35,846.

To all whom it may concern:

Be it known that I, KARL P. McELROY, a citizen of the United States, residing at Washington, in the District of Columbia, have invented certain new and useful Improvements in the Manufacture of Alkalies, of which the following is a specification.

- This invention relates to the manufacture of alkalies; and it comprises a process of 10 making alkalies and by-products wherein a solution of sodium chlorid or potassium chlorid is electrolyzed for the production of the corresponding alkali and chlorin, and the chlorin is formed or developed on an 15 anode bathed in an atmosphere of gas consisting of or comprising olefins, such gas being advantageously oil gas or a similar gas; all as more fully hereinafter set forth and as claimed.
- 20 In producing alkali by electrolysis of a brine solution the energy required is of course proportional to the voltage necessary. The voltage between terminals of any cell in actual operation depends upon a number of 25 factors, but in practice is usually 3.5 to 5 volts, the theoretical voltage being around 2.5. One element is the resistance of the fluid in circuit, and this is proportional to the thickness of the layer between the poles.
- 30 In the present conditions I rearrange the structure of the cell to lessen this thickness of electrolyte layer, and to this end I construct the cell with a pair of diaphragms spaced apart only far enough to allow a 35 good feed of brine therebetween. The cathode and the anode I locate beyond these diaphragms in special chambers. The cathode chamber may be maintained under any of the known conditions, as by filling 40 it with immiscible oil, with steam, with steam and furnace gases, etc. In the anode chamber however I further depart from the usual practice by maintaining an atmosphere of gases adapted to combine with the chlorin 45 when or as it is formed and to act as anodic depolarizers, thereby reducing the voltage and current consumption required for making alkali. The best gases for this purpose are the gaseous olefins, ethylene and propylene, and the best source is oil gas. Petroleum oils, such as gas oil, crude oil, still residua, etc., on exposure to a temperature of 600° C to 800° C. give gases which are rich in these olefins, ordinarily running 45 to 55 per cent. A similar gas is yielded by ordinary oil stills in distilling petroleum; and particularly in cracking operations. A gas which may be used is given by charring wood or coking coal under reduced pressure and at a low temperature. 55
- While the pure olefins or the other gases mentioned may be used, I regard a cleaned and purified oil gas as particularly suitable. The gas used should be scrubbed to remove oil, tar, sulfur, etc., and it is generally desirable to free it of acetylenic hydrocarbons, which may be done by passing it over hot copper at 250-300° C. or by scrubbing it with a solution of copper nitrate, with a magma of copper hydrate and water, etc. 60
- If it is desired to have substantially only ethylene and propylene present, that is if the presence of a little butylene or amylene is not desirable the gas may be scrubbed with chilled oil, or compressed to 60 to 90 65 pounds and cooled to condense out these bodies. Compressing, chilling and scrubbing with a little cold oil gives a particularly pure gas.
- The olefins on contact with chlorin may 70 react in either of two ways. One is a direct combination with it to form olefin chlorids; bodies in which the olefin is united with 2 atoms, or one molecule, of chlorin. Ethylene, C_2H_4 , thus gives ethylene chlorid, or 75 "Dutch liquid," ($C_2H_4Cl_2$) a heavy oily body insoluble in water and having an odor and many other properties resembling those of chloroform. The other reaction is one in which water takes part and a chlorhydrin, 80 or chlorinated alcohol, is produced. A molecule of chlorin, Cl_2 , reacts with HOH and C_nH_{2n} to produce HCl and $C_nH_{2n}OHCl$, or a chlorhydrin. Both reactions develop 85 much energy and thereby aid in anodic depolarization. 90
- Both the olefin chlorids and the chlorhydrins are desirable bodies for use in the arts as solvents and for other purposes, though they are wholly different in character. Both 95 are ordinarily produced in the present process though the proportions will vary with the conditions. They are readily separated since the chlorhydrins of the gaseous olefins are soluble in water and may be extracted 100 from a mixture by the aid of water.
- In the accompanying illustration, I have 105 shown a cell under the present invention and

adapted for use in the described process. In this showing,

Figure 1 is a central vertical transverse section;

5 Fig. 2 is a central longitudinal section along line $x-x$ of Fig. 1.

Fig. 3 is a view in section of a cell arranged for successive treatment of flowing gases; and

10 Fig. 4 is a perspective view of the same.

In the showing of Figs. 1 and 2 numeral 1 designates as a whole a cell divided into three chambers by two vertical diaphragms, 2 and 3, carrying, respectively, cathode 4 and anode 5. The cell may be constructed of concrete or other suitable material. In the anode chamber the walls and top may be interiorly varnished with a phenolformaldehyde composition to enable it to resist the 15 action of chlorin and acid. These compositions also withstand the action of olefin chlorids and chlorhydrins fairly well. The cathode may be wire gauze of copper or iron. The anode may be a metallic gauze 20 as well, or it may be carbon or other suitable material. Between the diaphragms is a brine chamber 6, provided with brine supply 7 and exit 8. The anode chamber is best constructed (see Fig. 2) as to cause gas 25 passing therethrough to pursue a circuitous or tortuous course in passing from inlet 9 to outlet 10. This may be provided by alternating depending and upstanding baffle walls 11 and 12, which also serve to 30 support the diaphragm. The diaphragms 12 stop somewhat short of the bottom of the chamber to afford free liquid communication from end to end. To provide this liquid space, the bottom of the anode chamber 35 may be somewhat depressed, as shown at 13 in Fig. 1.

In the operation of the cell of Figs. 1 and 2, the alkali forms on the cathode in the usual way and is disposed of as usual. 40 Hydrogen may escape at 14. The chlorin on the other hand develops or tends to develop on the anode and there combines with the olefins of the gas. What results depends upon the conditions. With a high current density, chlorin may actually form as gas, 45 at least to some extent, and this gas in mixing with the olefins will form the chlorids; at least to some extent. The extent depends upon the amount of water vapor present 50 which in turn depends upon the temperature. With an ample amount of water vapor chlorhydrins may be formed to the exclusion of chlorids. Where gas and evolving chlorin come into reaction on the 55 anode itself the tendency is to form chlorhydrins also, this tendency being more marked if there is free seepage through the diaphragm. In general both chlorids and chlorhydrins are formed; but their relative 60 proportions vary with conditions.

The chlorids being very heavy and insoluble in water tend to separate as an oily layer below the liquid accumulating in the anode chamber. Where chlorhydrins are formed alone they may or may not separate; this depending upon the amount of water in the anode chamber and that of the salt which is in solution therein. The chlorhydrins from oil gas dissolve in about twice their volume of water and to a somewhat extent in salt solutions. If the amount produced is too great for solution in the accumulating liquid, chlorhydrins will separate as an oily accumulation, sinking if the salt solution is 10 per cent. strong 70 or weaker; and floating if it is saturated. Where the amount of chlorids produced is relatively rather large, the chlorhydrins may be wholly dissolved therein since the olefin chlorids in contact with a water solution of chlorhydrins will extract the greater 75 part of the latter.

Presuming the cell is producing both, the oily layer may be washed with several portions of water to extract the chlorhydrins 80 and the solution so obtained added to the watery liquid withdrawn from the anode chamber. This liquid is next distilled, with or without neutralization to get rid of the hydrochloric acid which is a concomitant 85 of chlorhydrin formation. The chlorhydrins pass over with the first third of the water; and separate generally as oily drops in the first distillate. Using a good column still and returning saturated solution of 90 chlorhydrins distilling over, all the chlorhydrin may be obtained as such by distillation. The oily liquid so obtained may be dehydrated by salt or calcium chlorid, or by redistillation, and is then ready for 95 market. As all the chlorhydrins formed from oil gas have about the same boiling point (the boiling point ranges between 125° and 135° with the dry material), the mixture so obtained behaves for commercial 100 purposes like a unitary body.

The olefin chlorids obtained have a wider range of distillation and it is best to fractionate the product to obtain ethylene and propylene chlorids.

As will be noted in the above operation, I have cut down the energy required by making the electrolyte layer thinner than is possible where the anode must be inside the cell and by causing the chlorin to combine 115 as it is formed. The amount of energy saved by this anodic depolarization will depend very much on the physical conditions in the anode chamber; upon the rate at which the olefins can be brought into reaction with the chlorin. It may range from 120 10 to 15 per cent. or much higher, as both the heats of formation of olefin chlorids and of the chlorhydrins are heavily exothermic.

As a rule it is better to work cells such 130

as described in a plurality of units arranged in series as regards passage of gas, that is to feed gas from one cell to another, as this assists in good exhaustion and utilization 5 of the contained olefins.

In Figs. 3 and 4 is shown a multiunit cell of somewhat different construction as regards the anode chamber, adapted for successive treatment of a current of gas. Casting 20 is spanned by a number of diaphragms to form brine chambers 21, 22, 23, 10 24 and 25. Anode chambers A and cathode chambers C are arranged in alternation. The cathodes 26 may be wire gauze or netting. As anode material however there is used a freely pervious assemblage 27 of carbon or graphite fragments or bodies packed into each of the anode chambers A. Gas is led into the first anode chamber at 28, passes 15 downward therethrough and is taken by cross-pipe 29 to the top of the second anode chamber. It passes down therethrough and is taken by another cross-pipe 30 to the top of a third anode chamber, whence it 20 emerges at 31.

In the successive chambers it is converted into olefin chlorhydrins or chlorids, or both, in the same manner as in the previous device. The pervious carbon anode mass not 25 only operates as an efficient mechanical support for the pair of diaphragms between which it occurs, but also gives a large wetted surface for contact with the gas. The arrangement gives a good utilization of the 30 olefins of the gas since the gas may be discharged at 31 practically free of olefins. The device may also be used to give an approximate separation of the various olefin products since propylene and the higher 35 olefins react more quickly than ethylene. Using oil gas, the product obtained in the first chamber will contain mainly the propylene butylene and amylene compounds while in the third chamber the products will 40 be mostly ethylene derivatives. In making chlorhydrins for commercial use as a solvent it is better however to reunite these various 45 products since the mixed chlorhydrins are more desirable.

In another and copending application, Serial No. 35,505, filed June 22, 1915, I have described and claimed broadly the production of halohydrins or chlorhydrins by electrolysis of a halid or chlorid solution (such 50 as a solution of common salt, NaCl) in the presence of an olefinic gas, such as oil gas; but in such other application I describe more specifically the use of the olefins in connection with a liquid bath surrounding 55 the anode and limitation of current density and other conditions to preclude the sub-

stantial formation of olefin chlorids. This application contains certain disclosures occurring in my copending application Ser. No. 712,975 and as regards such matters is a 65 continuation of said application.

What I claim is:—

1. The process of making alkali and by-products which comprises electrolyzing a chlorid solution between an anode and a cathode and during such electrolysis maintaining 70 the anode bathed in a gas comprising an olefin.

2. The process of making alkali and by-products which comprises electrolyzing a 75 chlorid solution between an anode and a cathode and during such electrolysis maintaining the anode bathed in oil gas.

3. The process of making alkali and by-products which comprises electrolyzing 80 chlorid solutions in a plurality of cells having anodes and cathodes and during such electrolysis transmitting a current of gas comprising an olefin successively past the several anodes. 85

4. The process of making alkali and by-products which comprises electrolyzing chlorid solutions in a plurality of cells having anodes and cathodes and during such electrolysis transmitting a current of oil gas 90 successively past the several anodes.

5. The process of making alkali and by-products which comprises electrolyzing a thin layer of chlorid solution between a cathode and an anode, said anode being separated 95 from said solution by a diaphragm and maintained in an atmosphere of olefinic gas.

6. The process of making alkali and by-products which comprises electrolyzing a thin layer of chlorid solution between a cathode 100 and an anode, said anode being separated from said solution by a diaphragm and maintained in an atmosphere of oil gas.

7. The process of making alkali and by-products which comprises electrolyzing a 105 thin layer of chlorid solution contained between a pair of parallel diaphragms separating the anode and cathode therefrom and during electrolysis maintaining an atmosphere of olefinic gas in contact with said 110 anode.

8. The process of making alkali and by-products which comprises electrolyzing a thin layer of chlorid solution contained between a pair of parallel diaphragms separating 115 the anode and cathode therefrom and during electrolysis maintaining an atmosphere of oil gas in contact with said anode.

In testimony whereof, I affix my signature.

K. P. McELROY.
